UNITED STATES PATENT OFFICE.

JAMES C. COUPER, OF TERRE HAUTE, INDIANA, ASSIGNOR TO THE
STANDARD WHEEL COMPANY, OF CHICAGO, ILLINOIS.

DESIGN FOR A HUB-FLANGE.

SPECIFICATION forming part of Design No. 27,896, dated November 23, 1897.

Application filed July 30, 1897. Serial No. 646,564. Term of patent 7 years.

To all whom it may concern:

Be it known that I, JAMES C. COUPER, a citizen of the United States, residing at Terre Haute, in the county of Vigo and State of Indiana, have invented and produced a new and original Design for a Hub-Flange, of which the following is a specification, reference being had to the accompanying drawing, forming part thereof.

10 The figure is a side elevation of my newly-designed hub-flange.
Heretofore hub-flanges have been made which present, when viewed in elevation, as in the figure, an extension which extends out 15 flush with the end of the hub. Some are smooth and some are corrugated by having grooves parallel with the axis of the hub. In this flange the extension *a* extends out flush with the end of the hub which it incloses, and the 20 outer surface is grooved and checkered by two sets of V-shaped diagonal grooves which cross each other and leave a rough projection in the space between the intersections of the grooves.

The leading features of my design consist 25 in a flat circular flange *b*, a tapering portion *c*, which corresponds with the contour of the usual tapering portion of the hub of a wheel, and the cylindrical extension *a*, the outer surface of which is checkered by diagonal V- 30 shaped grooves or channels, and rough projections between the intersections of such grooves and channels.

Having described my new design, what I claim as my invention, and desire to secure 35 by Letters Patent, is—

The design for a hub-flange, substantially as herein described and shown.

In testimony that I claim the foregoing as my own I affix my signature in presence of 40 two witnesses.

JAMES C. COUPER.
